UNITED STATES PATENT OFFICE.

FRANK DUTCHER, OF MCKEESPORT, PENNSYLVANIA.

RAILWAY SIGNAL TORPEDO.

Application filed April 14, 1924. Serial No. 706,358.

To all whom it may concern:

Be it known that I, FRANK DUTCHER, a citizen of the United States, residing at Versailles Boro., McKeesport, in the county of Allegheny and State of Pennsylvania, have invented certain new and useful Improvements in Railway Signal Torpedoes, of which the following is a specification, reference being had therein to the accompanying drawing.

This invention relates to improvements in railway signal torpedoes and its object is to provide a new form of clip for connecting the rail engaging strap to the torpedo.

Many constructions have been devised and patented showing different forms of clips for connecting rail engaging straps to torpedo cases.

The primary object of my present invention is to so make and so attach a clip to the torpedo that the opposite ends of the clip automatically engage with the torpedo case or surrounding strengthening ring, the clip constructed for threading through openings in it a rail engaging strap.

Specifically my improvement pertains to a clip having its ends provided with pointed projections, the clip fitting within the ring or extension of the case, causing the projections to be embedded within the member engaged by them.

In the accompanying drawings:

Figure 1 is an inverted plan view of a torpedo case showing a clip embodying my present improvement applied thereto.

Figure 2 is a transverse sectional view of a case showing my improved clip applied to it.

Figure 3 is a sectional view at right angles to Fig. 2.

Figure 4 is a transverse sectional view of a torpedo showing my clip and a spring rail engaging strap held thereby.

Figure 5 is an enlarged plan view of my improved clip somewhat modified in construction.

Figure 6 is a transverse sectional view of a torpedo showing my clip applied to it, and holding a lead strap.

50 In showing my improvement I have adopted for the purpose of illustration a circular case, but I desire it understood that

the case may be of other forms without departing from my present invention, and that modifications may be made by those skilled in the art without changing the invention here involved.

In the drawings:

The case is composed of two telescoping cup-shaped members 1 and 2. These are of the ordinary construction, though the construction of this case may be varied without in any manner affecting my improved clip.

My improved clip essentially comprises a plate 3, preferably elongated, and the opposite ends of this clip are provided with a plurality of pointed projections 4, though the number of projections may be varied. Referring now to the illustration of Figures 1, 2 and 3, this clip is provided with two parallel corrugations 5 which as shown extend throughout the clip. The purpose of these corrugations is to prevent the clip from buckling when it is compressed by the surrounding ring 6^a.

In operation the clip is preferably applied to the torpedo by inserting it in a strengthening ring 6^a which will carry the ring out of a true circle. Then the case is placed in the ring and as it is being forced therein the ring is brought to a round or substantially round form whereby the clip is forced into the fibre ring. It will be understood that the form of torpedo here shown is of the non-flying type, that is to say, the case and the ring are preferably formed of paper or other fibrous material.

As shown this clip 3 is provided with two transversely extended openings 6 which lie between the longitudinal corrugations 5. The lead strap 7 passes through these openings and under the outwardly bulged portion 8 and extends outward as shown in Figure 6. This secures the strap firmly to the case and the case is firmly wedged in the ring 6^a. After the torpedo is constructed it is dipped in a water-proofing compound as is usual, and in which event the water-proofing compound enters and fills up the spaces making a water-tight torpedo.

When a spring rail engaging strap is applied to my improved clip it is made in two separate parts 9 and 10. In this case

the ends of the clip are cut out as shown at 11 forming a space between the center of the clip and the ring 6. The ends of the straps are made U-shaped as shown at 12 and these double around the portions 13 of the clip, while just outside of the parts 13 the straps are bent as shown at 14.

The straps whether lead or spring are attached to the clip before the clip is applied 10 to the torpedo, and the bent portions 14 act as a lock to hold the two parts of the strap in position.

I desire to call attention to the fact that the ends of the strap are bent into the 15 U-shape 12 and with the bends 14 before it is applied to the clip, and then it is applied by passing the long end through the inner opening 6 and out of the space 11. Thus the clip and the two parts of the strap are 20 then applied to the ring, and then the case pushed into the ring causing the projections 4 to bite into the ring. The completed torpedo makes a very permanent holder for the strap whether the strap is made of lead or a 25 spring.

In the construction shown in Figure 6 the outer case 1 has its wall 1' elongated so it extends beyond the part 2 of the case. In this arrangement the clip has its ends engaging the elongated wall 1', and the wall will be slightly deflected outward until the retaining and strengthening ring 6^a is applied when the projections will be forced into the extended wall of the case 1. This 30 is a modification of the construction that is disclosed in the other figures of the drawing. I desire it understood that the form of clip shown in Figures 4 and 5 can be used in the modified form of Figure 6 as well as when the case is made as in Figures 1, 2 and 3.

The improvement above described therefore involves the construction of the clip, and consequently involves the construction of the two-part spring strap in connection 45 with the clip.

In the construction the ring 6^a may be considered as comprising a part of the case in the broad acceptance of that term in the claims, except where the claims specifically state otherwise.

I desire it understood that modifications may be made in the construction without departing from the invention so long as it involves the features and operation described.

Having thus described my invention what I desire to secure and claim by Letters Patent is:

1. A railway signal torpedo comprising a case, a surrounding strengthening ring deeper than the said case and projecting beyond its bottom, and a clip having its ends extended and projecting and biting into the inner side of the said ring, for the 60 purpose described.

2. A railway signal torpedo comprising a case having a downwardly extending wall, and a transversely extending clip having its ends projecting and biting into the inner side of the said wall.

3. A railway signal torpedo comprising a case having an extended wall, of a transversely extending clip provided with longitudinal corrugations for the purpose described, the ends of the clip engaging the extended wall of the case, and a rail engaging strap connected with the clip.

4. A railway signal torpedo comprising a case having a downwardly extended wall, of a clip having its ends engaging the inner side of said wall, the said clip provided with two openings, and a spring rail engaging strap comprising two parts, the end of each part passing through the openings and doubled around the clip for connecting it therewith, the spring strap normally bent downwardly and inwardly, whereby the parts are held in position when applied to the head of a railway rail.

5. A railway signal torpedo comprising a case having an extended wall, a clip engaging the said wall, said clip having two openings at opposite ends, of a spring rail engaging strap passing through the said openings and doubled around the clip, said strap having bent portions beyond the doubled portions, whereby the strap is locked against endwise movement.

6. A railway signal torpedo comprising a case having an extended wall, a clip engaged by the said wall, the said clip having strap engaging openings, of a two-part spring, the upper ends of the spring bent to interlock with the said clip and the extended wall, thereby locking the two-part strap thereto.

7. An improved railway signal torpedo comprising a case having an extended wall, a clip engaging the said wall, the said clip having strap openings, of a two-part spring strap, the upper ends of the two-part strap normally bent downwardly and inwardly passing through the said openings thus providing an elongated bearing when the two-part strap is separated for application to a railway rail.

8. An improved clip for railway signal torpedoes comprising an elongated member, the said clip having a longitudinal corrugation and openings for connecting a rail engaging strap thereto.

9. An improved clip for railway signal torpedoes comprising an elongated member having its ends constructed to lock with the torpedo case, the said member having parallel longitudinally extended corrugations and openings to receive a rail engaging strap.

10. An improved clip for railway signal torpedoes comprising an elongated member

having its ends provided with pointed projections for engaging with a case, and longitudinal corrugations and strap openings between the corrugations.

5 11. An improved clip for railway signal torpedoes comprising an elongated member having longitudinal corrugations, the center of the ends of the member cut away, and a clip provided with transversely extending strap openings, for the purpose described.

10 12. An improved clip for railway signal torpedoes comprising an elongated member having the center of its ends cut away, longitudinally extending corrugations, strap openings extending transverse the member and located between the corrugations, for the purpose described.

15 13. An improved clip for railway signal torpedoes comprising an elongated member, cut away between its ends and having the remaining portions of its ends provided with pointed projections, said member having longitudinally extending corrugations,

and strap openings located between the corrugations.

20 14. An improved railway signal torpedo comprising a case, a surrounding strengthening ring of greater depth than the said case and extending from one side of the case, and a clip having its ends held by the said ring, and a rail engaging strap connected with the clip.

25 15. An improved railway signal torpedo comprising a case, a strengthening ring surrounding the said case and of greater depth than the case, said ring extending from one side of the case, a clip held to the case by the extended portion of the ring, said clip constructed for the attachment of a spring 40 rail engaging strap, said strap being bent to interlock with the clip and with the extended portion of the ring to hold it in place and prevent its removal.

30 35 In testimony whereof I hereunto affix my 45 signature.

FRANK DUTCHER.
